UNITED STATES PATENT OFFICE.

HARRY C. BUHOUP, OF CHICAGO, ILLINOIS.

BRAKE-BEAM.

SPECIFICATION forming part of Letters Patent No. 721,664, dated March 3, 1903.

Application filed June 17, 1902. Serial No. 112,069. (No model.)

To all whom it may concern:

Be it known that I, HARRY C. BUHOUP, a citizen of the United States, residing at Chicago, in the county of Cook, State of Illinois, 5 have invented certain new and useful Improvements in Brake-Beams; and I hereby declare the following to be a full, clear, and exact description of the same, reference being had to the accompanying drawings, in 10 which—

Figure 1 is a plan view, partly broken away, of a brake-beam embodying my invention. Fig. 2 is an enlarged detached end view of the lever-post or strut. Fig. 3 is an enlarged 15 transverse section of the strut or lever-post and the lever-block. Fig. 4 is an enlarged longitudinal central section of the lever-post or strut and the lever-block. Fig. 5 is an enlarged detached plan view of the lever-block; 20 and Fig. 6 is a longitudinal central section of the lever-post and lever-block, showing a modified means for actuating the take-up block of the slack-adjuster.

Like symbols refer to like parts wherever 25 they occur.

My invention relates to the construction of brake-beams, and has for its several objects to provide in a single structure simple and efficient means for readily converting the 30 brake-beam from a right-hand beam to a left-hand beam, for positioning the fulcrum of the brake-lever to any requirement arising from different methods of hanging, different lengths of connecting-rods, or peculiarities of 35 particular trucks, and, finally, to either manually or automatically compensate for wear and eliminate slack from the brake system. Those familiar with railway practice are 40 aware that the relation of the lever-fulcrum to the beam or back member of the beam or its distance therefrom varies according to the hanging of the beam, which latter is determined by the standard of the particular railroad using the beam, also that the varying 45 lengths of pull and connecting rods in the different brake systems or the peculiar requirements of some trucks affect the position of the fulcrum of the brake-levers for efficient work, and, further, that the wear of pivot-holes, brake-shoes, and other parts of the 50 brake systems inducing slack or lost motion all affect the efficiency of the brake system

and must be eliminated or counteracted to obtain satisfactory results, especially where power or air brakes are used. To effect the 55 first of these several purposes, I combine with the lever-post of a brake-beam having slideways a reversible sliding lever-block capable of being inserted and withdrawn laterally of the post, and such a construction embodies 60 one feature of my invention.

To effect a second purpose of my invention, I combine with the lever-post of a brake-beam having slideways a sliding lever-block movable longitudinally of the post and one or 65 more liners interposed between the post and sliding lever-block, and such a combination embodies a second feature of my invention.

To effect a third purpose of my invention, I combine with a lever-post a movable fulcrum for the lever and an incline for automatically shifting the movable fulcrum co- 70 etaneous with the slack arising from any increment of wear in the system to compensate for said wear in the system, and such a construction or its equivalent embodies a third 75 feature of my invention.

There are other minor features of invention, all as will hereinafter more fully appear. 80

I will now proceed to describe my invention more fully, so that others skilled in the art may apply the same.

Though the lever-post embodying my invention is equally applicable to solid beams, 85 yet for the purposes of the present case I have chosen to illustrate it as constituting the strut C of a trussed brake-beam, of which A is the compression member and B the tension member. 90

The lever-post C is preferably in the form of a frame or guideway for a sliding lever-block, said frame composed of the side bars 1 1, connected at each end by the cross-bars 2 3, the former of which is provided with means 95 for attaching the same to the beam (in the present instance a sleeve 2^a for the reception of the compression member A) and the latter with a hanger-eye 3^a for a third suspension-hanger and also in the present instance with a groove or seat 3^b for the reception of the tension member B. The side bars 1 1 of the frame are each provided with two inwardly-projecting flanges, (see cross-section, Fig. 3,) 100

the lower of which, 1^a, extends the whole length of the side bar 1 and is sufficiently wide to lap well under the sliding lever-block and afford it ample support, while the upper flange 1^b, which is of less width, terminates a short distance from the inner end of the post (see 1^c, Figs. 1 and 4) to permit the introduction of the lugs or pintles of the sliding lever-block. The groove 4 between said flanges 1^a 1^b forms the slideway for the sliding lever-block, and the openings 1^c in the flange 1^b permit the introduction of the slide laterally of the post, as will hereinafter appear. The outer cross-bar 3—in the present instance that end of the post which receives the tension member B—is provided with a wedge-box 5, having its inclined face 5^a corrugated to engage like corrugations on the corresponding face of the wedge, its side toward the sliding lever-block open, and its top closed and provided with a spring-recess 5^b to receive a spring 6, whose lower end exerts its force on a wedge 7, inserted in said wedge-box. The corrugations on the incline 5^a and the wedge 7 may be omitted, if desired.

8 indicates a sliding lever-block longitudinally movable in the slideways 4 of the post C. This lever-block 8, the mid-width of which is substantially equal to the distance between the edges of the narrow flanges 1^b, will when the block is in position have a full-length bearing at each side on the wider flanges 1^a, so as to afford ample support for the block against any force exerted by the lever on the lever-block. The lever-block at each end is provided with laterally-projecting lugs or pintles 8^a of such form as to permit them to be introduced laterally into the slideways 4 through the openings 1^c in the flange 1^b and to be turned when in the slot so as to bring the plane of the lever-block 8 within the plane of the frame or lever-post C.

9 indicates the lever-slot of the lever-block, said slot intersecting the plane of the lever-block at the usual angle and bordered by lugs or ears 9^a, which project on opposite sides of the lever-block in planes parallel with the plane of the lever-slot and are perforated, as at 9^b, to receive the fulcrum-pin of the brake-lever 10, which latter when in position (see Fig. 3) crosses the lever-slot 9 at right angles. The outer faces of the pintles 8^a or the ends of the lever-block are preferably slightly flattened, as at 8^c, (see Figs. 4 and 6,) to insure square contact between the same and one or more liners 11, which may be interposed for the purpose of positioning or adjusting the fulcrum-point of the brake-lever 10 or in the absence of such liners 11 to obtain a square contact for the vertical face of the slack-take-up wedge 7.

The elemental construction being of the general character hereinbefore pointed out, the parts may be assembled by first inserting the spring 6 within its recess in the wedge-box, then inserting the wedge 7 in its proper position, (see Fig. 4,) next introducing the

number of liners 11 required to set or hold the lever-fulcrum the desired distance from the beam, (or compression member A,) and finally introducing the sliding lever-block 8. In introducing the sliding lever-block 8 it is held at right angles to the post, so that the leading lugs or pintles 8^a may be entered in the slideways 4 through the openings 1^c in flanges 1^b, after which the block is moved laterally toward the front end of the lever-post until its other pintles can be lowered and introduced through the openings 1^c into slideways 4, when the lever-block is turned on its leading pintles 8^a to bring the block 8 into the plane of the frame or lever-post C, and is finally moved forward in the slideways 4 until it comes in contact with the liners 11 or the slack-take-up wedge 7, as the case may be. Before introducing the lever-block 8 into the slideways 4 that end of the block must be taken as the leading end which will cause the plane of the lever-slot to correspond with the desired plane of the brake-lever, (right or left hand lever.) After the beam has been set up if it is desired to change the beam from a right hand to a left hand, or vice versa, all that will be required will be the withdrawal of the block and the reversal of its ends before replacing the same. The brake-beam having been set up either with or without liners 11 and it being necessary to alter the position of the fulcrum-pin of the brake-lever, the same can be done by withdrawing the sliding lever-block from the ways 4 and inserting or removing liners 11, as the case may require.

When a brake-beam provided with the slack-take-up wedge 7 is first put in service, there being no wear of the brake-shoes or slack in the system, the wedge 7 will retain its highest position, as indicated in Fig. 4 of the drawings; but as soon as any slack arises in the system from brake-shoe wear or otherwise the take-up wedge 7 will sink by gravity, assisted, if necessary, by the pressure of wedge-spring 6, thus shifting the fulcrum of the brake-lever 10 from time to time to take up the slack and compensate for brake-shoe wear. The inclined faces of the wedge-box and wedge being roughened or corrugated will prevent the wedge from giving back or receding under the jars and shocks incident to its position.

In the modification shown in Fig. 6 of the drawings the take-up wedge 7 is positively operated to take up slack (or shift the fulcrum of the brake-lever) by means of a tap-pet-arm 6^a on the brake-lever 10, which strikes the top of the wedge whenever the brake-lever 10 exceeds its normal movement or travel in applying the brakes. It will be noted that in the construction shown in Figs. 1 and 4 the slack is taken up when the brakes are released, and the take-up wedge 7 can then act by gravity or with slight inducing pressure; but in the modified construction shown in Fig. 6 the slack will be taken up as the brakes

are applied and the lever force will be exerted to aid the wedge take-up in its operation. It will also be noted that the wedge or incline acts continuously—that is to say, each 5 increment of slack is taken up coetaneous with the wear which gives rise to it and not after a certain accumulation of slack has taken place.

Having thus described my invention, what I claim, and desire to secure by Letters Patent, is—

1. In a brake-beam, the combination with a lever-post, of a longitudinally-sliding lever-block, substantially as and for the purposes 15 specified.

2. In a brake-beam, the combination with a lever-post having a guideway comprised of parallel flanges said flanges having lateral openings for the passage of lugs or pintles on 20 a lever-block, of a sliding lever-block having laterally-projecting pintles, substantially as and for the purposes specified.

3. In a brake-beam, the combination with a lever-post having a guideway comprised of 25 parallel flanges of unequal length, of a lever-block having laterally-projecting lugs or pintles, substantially as and for the purposes specified.

4. In a brake-beam the combination with 30 a lever-post having guideways comprised of parallel flanges of unequal length the narrow flanges having slots for the passage of lugs or pintles on a lever-block, of a sliding lever-block provided with laterally-projecting lugs 35 or pintles, substantially as and for the purposes specified.

5. In a brake-beam, the combination with a lever-post having guideways, of a sliding

lever-block, and detachable liners, substantially as and for the purposes specified.

6. The combination with a brake-beam and its brake-lever, of a movable fulcrum for the brake-lever, an incline, and means actuated by the incline for shifting said movable fulcrum, substantially as and for the purposes 45 specified.

7. In a brake-beam, the combination of a movable lever-block, and a slack-take-up device, substantially as and for the purposes specified.

8. In a brake-beam, the combination with a lever-post, of a movable lever-block, a wedge take-up device, and means for inducing a movement of the take-up device, substantially as and for the purposes specified.

9. In a brake-beam, the combination with a lever-post having guideways, of a sliding lever-block, and a spring-pressed wedge, substantially as and for the purposes specified.

10. In a brake-beam, the combination with a lever-post, of an adjustable brake-lever fulcrum, and a wedge slack-take-up device, substantially as and for the purposes specified.

11. The combination with a brake-beam and its lever, of a movable fulcrum for the brake-lever, and means mounted thereon for automatically shifting said fulcrum simultaneously with the creation of the slack, substantially as and for the purposes specified.

In testimony whereof I affix my signature, 70 in presence of two witnesses, this 12th day of June, 1902.

HARRY C. BUHOUP.
